RELAY

Henry C. Harrison, Port Washington, N. Y., assignor to Bell Telephone Laboratories, Incorporated, New York, N. Y., a corporation of New York

Application January 7, 1948, Serial No. 993

11 Claims. (Cl. 200—104)

1

This invention relates to new and useful improvements in electromagnetic relays and more particularly to relays used in telephone switching circuits.

Designers of electromagnetic devices have constantly sought to develop general purpose relays of greater efficiency, compactness, cheapness of manufacture and maintenance, facility to establish different combinations of electrical circuits, and freedom from mechanical or electrical failure. In accordance with these aims, the applicant has developed a multicontact relay embodying features directed at improvements in the above-mentioned factors, and has filed application for Letters Patent thereon, Serial No. 693,595, filed August 28, 1946 now Patent No. 2,562,091, July 24, 1951. Subsequent research has led to the development of further advancements in the art as evidenced by the improvements contained herein, including a disclosure of a new and useful means for rapidly, easily, and economically changing the variety of combinations in which circuits may be controlled, a disclosure of an improved structure to expedite assembly and disassembly and to permit easy interchangeability of coils to meet various requirements, provision for the insertion of condenser or resistance elements in circuit with the energizing windings, and various other improvements which will become apparent later in the specification.

An object, therefore, of this invention, is to attain a high degree of efficiency, compactness and economy of manufacture and maintenance in an electromagnetic relay.

A further object of this invention is to obtain a high degree of adaptability in a relay in order that it may be readily adapted to meet a particular set of requirements by the simple interchange of a few critical parts.

The applicant has accomplished these purposes by utilizing the advances in molded wire spring design, as disclosed in the above-cited application, in combination with a structure arranged to firmly hold a readily removable magnetic pole-piece thereby providing for interchangeability of energizing coils. The adapting of the relay to make or break a variety of circuits in different combinations, which will henceforth be referred to as the coding of the particular combination, has been accomplished by the use of a removable fixed card mounted on a support structure and notched to provide apertures for the contact springs at a point near their outermost or contact ends, and the provision of a removable active card associated with the armature of the

2

relay and having apertures to accept the contact springs at a point adjacent the fixed card.

In the embodiments of the invention disclosed herein, a core of magnetic material is provided with an energizing coil. Provision is made to render the core readily detachable from the main structure of the relay, and the coil may be wound so as to be slidably removable from said core or may be fixedly secured thereto. The ready interchangeability of the core and coil assembly thereby provided permits the varying of the characteristics of the relay by means of the use of different coils and also by means of the use of cores of various cross-sections, areas, or materials. Wire coil leads are arranged to be readily disconnectable from the coil terminals and may be mounted in a base member having a hollow center portion designed to accept resistance or condenser elements connectable in parallel or series with the coil windings, as shown in the first embodiment of the invention presented herein. A flat rectangular armature is mounted so as to be attractable by said core and is supported by an armature spring mounted in the spring pile-up assembly at the rear of the relay. Two series of wire contact springs supported in insulating blocks mounted in the pile-up assembly extend toward the front of the relay in approximate parallelism. Each spring in the upper bank consists of a single round wire bearing a small flat contacting surface, and is arranged to make contact with a mating pair of round springs in the lower layer. The twin springs in the lower bank are each provided with flat contacting surfaces and may be constructed of wires of slightly different diameters to cause the periodicity of vibration of the two wires to be slightly different in order to avoid contact chatter. The action of the contact springs is controlled by two cards of insulating material, one of which is fixed or stationary and is removably attached to a supporting bracket, and the other of which is active or movable and is removably associated with the armature. In the particular embodiments disclosed herein each of said cards is formed in two sections in order to render the card easily replaceable for changes in coding. Each of the sections is notched or apertured as required to accept the contact springs, and the coding or particular combination of make and break connections is controlled by the notching of the upper fixed card and the lower movable card. In the arrangements presented herein contact springs in the lower bank are pretensioned upwardly

against the lower section of either the fixed or movable card depending upon the coding.

An outstanding feature of the relay is the reduction of parts and simplification of assembly provided by the construction. As will be more clearly indicated later in this specification, the major associated parts are so constructed that the relay may be assembled or disassembled without the use of tools.

The invention may be more fully understood by reference to the accompanying drawings in which:

Fig. 1 is an exploded view of a relay embodying the invention;

Fig. 2 is a plan view of the relay shown in Fig. 1;

Fig. 3 is an elevational view of the relay shown in Fig. 1;

Fig. 4 is an end view of the relay shown in Fig. 1 with the cover removed;

Fig. 5 is a section through 5—5 of Fig. 3 with the cover removed;

Fig. 6 is an elevational view substantially through 6—6 of Fig. 4 showing the relationship of the cards to a set of "make" contacts;

Fig. 7 is an elevational view substantially through 7—7 of Fig. 4 showing the relationship of the cards to a set of "break" contacts;

Fig. 8 is a plan view of a second embodiment of the invention with the cover removed;

Figs. 9 and 10 are elevational, and end views, respectively, of the embodiment shown in Fig. 8, with the cover in place; and

Fig. 11 is a section through 11—11 of Fig. 9.

Referring now to the embodiment of the invention shown in Figs. 1, 2, 3 and 4, a substantially T-shaped core 1 supports an energizing coil 2 which is formed so as to slidably engage the core 1 and which has a front spoolhead 3. Projections 4 at the extremes of the cross bar of the T-shaped core engage suitably shaped slots in the relay case or support structure 5 in order that the core may be firmly retained in place and yet readily removed by springing the case outwardly at each side. The rear of the core 1 is supported by the lower block 6 of the three blocks 6, 7 and 8 which comprise the spring pile-up assembly. An extending tongue 9 of the flat spring 10 clamped between the lower block 6 and intermediate block 7 is arranged to press downwardly upon the rear of the core 1 to retain it in proper position. The outer portions of the spring 10 extend forwardly and are affixed to the armature 11 at point 12 so as to bias the armature 11 upwardly in its unoperated position. The armature 11 is in the shape of a rectangular frame with the base cross-piece 13 thereof resting in contact with the core 1 and with the top cross-piece 14 extending parallel to the cross bar of the substantially T-shaped core 1. The armature 11 is normally biased upwardly by the spring 10 against the back stop which is disclosed as a bolt 15 affixed to the core 1 and having an adjustable nut 16 thereon. The back stop bolt 15 and nut 16 may be of brass or similar non-magnetic material or may be of magnetic material if the delayed operation obtained thereby is desirable.

In order that the energizing coils may be readily interchanged to meet the requirements for a particular use of the relay, the coil 2 is removably mounted upon the core 1 as above described. To facilitate the electrical connection or disconnection of the coil the spoolhead 3 has two terminals 17 affixed thereto which are connectable to the ends of the coil winding. Each terminal 17

has a slot therein of sufficient width to accept the coil leads 18 which are molded in or otherwise attached to the lower block 6 and extend rearwardly therefrom to provide wiring terminals 19. The leads 18 are offset from their respective slots in the terminals 17 so that when they are sprung inwardly to engage with the slot, sufficient pressure is applied by the elasticity of the leads to provide good electrical contact between each lead 18 and its associated terminal 17. Additional assurance of good electrical contact may be secured by soldering the connection. As may best be seen by reference to Figs. 1 and 3, the lower block 6 is formed with a hollowed out portion in which may be placed impedance elements 20 connectable in series or parallel with the coil winding in order to provide contact protection or to perform other circuit functions.

The contact springs by means of which external electrical circuits may be controlled are located in two banks. The upper contact springs 21 are molded or otherwise fixed in spaced relationship to each other in the upper block 8 while the lower contact springs 22 are similarly fixed in the intermediate block 7. The blocks 7 and 8 have each been constructed in two sections separated one from the other to provide a dampening effect upon the action of the contact springs. The blocks 7 and 8 are serrated along their rearmost edges with the projections of the upper block 8 in alignment with the depressions of the intermediate block 7. With a contact spring (or pair of springs) protruding from each projection and from each recess and with the terminal ends of adjacent springs in a bank bent apart in a vertical sense, it is seen that maximum clearance is obtained between the spring terminals to expedite the wiring of the relay. The three blocks 6, 7 and 8 are fixed in positive relationship to each other by means of mating studs and orifices in adjacent blocks and are locked together in fixed relationship to the case 5 by a C-shaped clamp 23 which bears upon the upper block 8 and extends downwardly along each side of the case 5. Tongues 24 on each side of clamp 23 extend inwardly to engage apertures in case 5, thereby providing a positive locking action. The lower edges of the clamp 23 are slightly fluted to provide surfaces which may be grasped to remove the clamp.

The round wire contact springs 21 and 22 extend forwardly in approximate parallelism with each other and with the core 1. The lower springs 22 are shown as passing through the intermediate block 7 at a slight angle in order that these springs 22 may be under a pretension when in place as shall be described hereinafter. Each spring 21 in the upper bank is bent downwardly at a point near the contacting end and has a small flat contacting surface or plate 25 which may be of or inset with precious metal. Each upper spring 21 mates with two of the round wire springs 22 in the lower bank, and therefore the lower springs 22 are arranged in pairs and may hereinafter be referred to as the "twin springs." The lower springs 22 are provided with small rectangular contact surfaces 26 and are so positioned that each plate 25 on an upper spring 21 is aligned with the plates 26 on the mating twin wire springs 22. In order to reduce the possibility of contact chatter, the springs in a pair of twin springs 22 may be of slightly different diameters to cause the periodicity of vibration of the two wires to be slightly different.

The action of the contact springs is controlled

primarily by a fixed operating member or "card" and a movable operating member or "card", and for facility of manufacture, assembly and coding, each of these cards has been constructed in two sections. The fixed card of insulating material comprises a lower fixed card 27 and an upper fixed card 28, both of which are mounted in fixed relationship to the case 5. The lower fixed card 27 comprises an insulating plate of substantially rectangular shape, and is provided with tongues 29 extending outwardly at each end to engage orifices in the case 5 so that the card is maintained in a fixed position relative to the body of the relay. As may be seen in Figs. 1 and 5, two rows of apertures are punched in the card 27, the lower apertures 30 accepting the twin springs 22 and the upper apertures 31 accepting the upper springs 21. The upper apertures 31 are each provided with a vertical slot so that the upper springs 21 are free to move vertically upward except as prevented from so doing by the upper fixed card 28 as shall be hereinafter disclosed. The apertures may in each case be suitably notched to align the contact springs laterally. The upper fixed card 28 has a rectangular main portion provided at each end with a tongue 32 which is engageable in slots cut at an angle in case 5. A plurality of finger-like projections 33 extend from the main portion and the ends thereof are insertable a short distance through the apertures 31 in the lower fixed card 27. The number and location of these fingers is determined by the coding of the relay, but as may best be seen in Fig. 5, any upper contact spring 21 passing through an aperture 31 in lower fixed card 27 which has one of the fingers 33 associated therewith is effectively locked in a fixed position.

The movable card comprises a lower movable card 34 and an upper movable card 35. As may be seen in Figs. 1 and 4, the lower movable card 34 is an insulating plate of substantially rectangular shape having two rows of apertures punched therein. The lower apertures 36 accept the twin contact springs 22 and the upper apertures 37 accept the upper contact springs 21. The apertures as shown in Fig. 4 are of various depths as required by the coding of the particular embodiment. At the lower edge of the lower movable card 34 two tongues 38 are extended which engage in notches in armature 11. The upper movable card 35 comprises a flat metal C-shaped bail and an insulating member 39 which may be cylindrical. The upper movable card 35 is arranged to hold the lower movable card 34 in fixed relationship with the armature 11, and therefore the bail 35 has projecting flanges to retain the card 34 in relation to itself and apertures to accept projections 40 on the armature 11 to render the movable card combination operatively integral with the armature 11. Upper contact springs 21 passing through the shallow apertures 37 are effectively positioned in the movable card assembly. Those springs 21 which are associated with the larger apertures 37 are free to move through a short vertical distance. As may be seen, the coding of the relay or the particular "make" and "break" combination is controlled by the shape of the apertures in the lower movable card 34 and the location and number of the fingers on the upper fixed card 28. Therefore, any desired coding within the size limitations of the relay may be obtained by the exchanging of only these two critical parts.

Referring now to Fig. 6 in which a section is

shown through one of the "make" contacts sets with the relay in an unoperated position, the upper spring 21 is not controlled by the fixed card at any time, but is held between the two sections of the movable card. The lower twin contacts 22 are not directly affected by the movable card at any time during operation, but are pretensioned upwardly against the fixed card. Upon operation of the relay the movable card is moved downwardly by the armature 11, the upper spring 21 moves into contact with lower twin springs 22, and any further downward motion will force the lower springs 22 downward against their pretension.

Referring now to Fig. 7 in which a section is shown through one of the "break" contact sets with the relay in an unoperated position, the upper spring 21 is firmly held between the upper 23 and lower 27 sections of the fixed card and the lower twin springs 22 are pretensioned upwardly against spring 21. Upon operation of the relay, the movable card is pulled downward which forces the twin springs 22 downward. Inasmuch as the spring 21 is held immobile by the fixed card, the electrical connection is broken. "Break-before-make" or "make-before-break" combinations can be obtained by small variations in the depth of the lower apertures 36 in the lower movable card 34 as may best be seen in Fig. 4.

It may be seen that by releasing the clamp 23 and the bail 35, the relay may be disassembled without recourse to tools.

Provision is made for the mounting of the relay by the affixing of a nut 41 at the rear of the case 5.

The independent action and the large predilection of the two twin wire springs, and the freedom of lateral movement of the springs within the boundaries of the card apertures has resulted in a very superior freedom from openings due to dust particles. However, an individual protective cover may be provided comprising a sheet metal sheath 42 (Figs. 2 and 3) so formed as to slide over the outer surface of case 5, and an end plate 43 which may be of a transparent material for ease in viewing the operation of the relay. The cover may be retained upon the relay by any suitable means with the method disclosed herein comprising a portion 44 on one side of the cover pressed inwardly sufficiently to provide a friction fit between the case 5 and the cover sheath 42.

A second embodiment, as depicted in Figs. 8, 9, 10 and 11, utilizes a similar spring and card assembly to that previously described, but a modified core and armature structure has been combined therewith. The core is constructed in two portions so arranged that without increasing the over-all size of the relay the coil may be located at a sufficient distance from the contact springs to permit the placing of a cover over the contact springs only, as will be subsequently described. Various tests have indicated that the fumes arising from the energizing coil are an appreciable cause of contact corrosion, and therein lies the desirability of separately enclosing the contact spring assembly. A small rectangular armature pivotally mounted about one of its edges has been employed in this embodiment in order that the reduced mass of the armature may permit a reduction in the power consumption of the relay.

Referring now to Figs. 8, 9, 10 and 11, an upper set of contact springs 45 mounted in an upper insulating block 46 are arranged to mate with twin wire springs 47 mounted in a lower insulating

block 48. The blocks 46 and 48 have mating studs and apertures 49 to retain them in fixed interrelationship and the lower block 48 is properly apertured to accept studs 50 on the core rear pole-piece 51. The blocks 46 and 48 and the rear pole-piece 51 are locked together into a spring pile-up assembly by a C-shaped clamp 52 which is removable by springing the side portions thereof outwardly.

As may best be seen in Fig. 9, the two-piece core comprises a rear pole-piece 51 and a front pole-piece 53. The rear pole-piece 51 is of substantially rectangular shape and has near its center a tongue 54 stamped therefrom extending downwardly and thence rearwardly. Projections 55 on each side of the rear pole-piece 51 are engageable in apertures in the case or support structure 56. A portion 62 at the rear is bent downwardly and is apertured to provide a means of mounting the relay and to accept the coil terminals as will be hereinafter described. The front pole-piece 53 is a substantially U-shaped member of magnetic material having a shank extending forwardly of and in a parallel plane with the rear pole-piece 51 and associative with the tongue 54. The upper leg of the front pole-piece 53 has a widened portion 57 lying in plane with the rear pole-piece 51 and separated therefrom by a suitable air gap. Projections 58 on each side of the widened portion 57 are engageable in apertures in the case or support structure 56. A rectangular notch cut in the rear of the shank of the front pole-piece 53 is aligned with a keyhole shaped notch in the tongue 54 of the rear pole-piece 51 and the two portions of the core are firmly held together by means of a removable wire clip 59. The energizing coil 60 is secured upon the shank of the front pole-piece 53 with space provided for the placing of insulation covered coil terminals 61 between the coil and the core. These coil terminals 61 extend rearwardly and pass through apertures in the downwardly extending portion 62 of the rear pole-piece 51 although the contact-protection network disclosed in connection with the first embodiment of the invention may be utilized. By detaching the coil leads from the coil terminals 61, unsnapping the wire clip 59, and springing the hook-shaped extensions 63 of support structure 56 slightly outward, the front pole-piece 53 and the coil 60 may be removed from and replaced in the relay with a minimum of disturbance of the remainder of the relay, and without the necessity for removing the relay from its mounting. In this fashion the front pole-piece and coil assembly may be readily exchanged to meet a variety of requirements such as speed of operation and release, load capabilities, power consumption, etc. Coils of various numbers of turns of various sizes of wire may be used in different situations, and front pole-pieces of different areas, cross-sections or materials may be desirable to change the magnetic characteristics of the relay.

The previously mentioned case or support structure 56, of non-magnetic material, serves as a means of maintaining certain of the elements of the relay in fixed relationship. Of a substantially U-shape, it is formed with circular bends 64 to permit the springing of the sides outwardly for attaching the several elements thereto and has a forwardly extending bottom portion 65 serving to provide an additional support under the core pole-pieces 51 and 53.

A rectangular, low-mass armature 66 is pivotally mounted so as to bridge the gap between the pole-pieces upon energization of the coil. Portions 67 extend forwardly at the front of the

armature and engage overhanging portions of the backstops 68 mounted in the front pole-piece 53. A flat lower armature spring 69 which may be of either magnet or non-magnetic material rests on the rear pole-piece 51, is locked between the lower insulating block 48 and the rear pole-piece 51, and has an extending portion 70 which is riveted or otherwise attached to the armature 66.

The mating contact springs 45 and 47 are controlled by fixed and movable cards, and as in the previous embodiment, may be arranged to "make" upon operation, "break" upon operation, or may be arranged to "transfer" connections by strapping suitable terminals together and regulating the mating springs to "make-before-break" or "break-before-make" as has been commonly performed in the art. Referring particularly to Figs. 9 and 11, the fixed card of insulating material comprises a lower fixed card 71 and an upper fixed card 75. The lower portion 71 has a plurality of notches along the upper and lower edges thereof to accept the contact springs, and is retained in a fixed position by tongues 72 extending outwardly at each end and engageable in apertures in the case 56. Further extending portions 73 pass through apertures in the upper armature spring portion 74, through apertures in armature 66 and into contact with the core front pole-piece 53. The centermost extending portion 70 also engages an aperture in the lower armature spring 69 and extends into an aperture in the front pole-piece 53 as may best be seen in Fig. 11. The upper fixed card 75 is suitably notched and is maintained in position by being pinned or otherwise attached to upper armature spring portion 76 as will hereinafter be described.

Referring now to Fig. 10, the movable card comprises a lower movable card 77 and an upper movable card 78. The lower portion 77 is suitably notched along its upper and lower edges to accept the contact springs and the projections 79 thereby formed along the lower edge rest in contact with the armature, passing through apertures in the upper armature spring portion 74 which is riveted or otherwise attached to the armature. The centermost projection 79 passes through apertures in spring portion 74 and armature 66 to position the card laterally. The upper movable card 78 need not be notched, but is arranged to rest firmly against the lower movable card 77 at the lower edge, and is retained in place by the upper armature spring portion 80 as will be later described.

This embodiment has been "coded" so that the inner six mating sets will "make" upon operation of the relay, and the outer three mating sets on each side will "break" upon operation of the relay. Considering now the "make" sets, the upper springs are firmly held by the movable card and the lower springs are pretensioned upwardly against the fixed card. Upon operation of the relay and the consequent downward motion of the movable card, the upper springs are brought into contact with their mating lower twin springs. In the case of the "break" sets, the upper springs are firmly held by the fixed card and the lower springs are pretensioned upwardly so as to be in intimate electrical contact with their mating upper springs. Upon operation of the relay, the movable card, in its downward movement, forces the lower springs downwardly thus breaking the electrical connections.

The upper armature spring, previously mentioned, is ingeniously designed to serve the multiple functions of retaining the upper fixed card

75 in position, retaining the upper movable card 78 in position, and serving as an operating link between the movable card and the armature 68. The upper portion 76 (Figs. 8 and 9) has projections 81 thereon which engage the angled slots in the case or support structure 56 so that the forward edge of the upper portion 76 presses downwardly against the upper fixed card 75 to which it is attached by means of pins 82. U-shaped portions 83 of the upper armature spring extend rearwardly and thence forwardly, culminating in the portion 80. The spring has been formed in this shape to permit the portion 83 to spring with the movement of the armature while the portion 76 remains stationary. The portion 80 has a plurality of hook-like projections 84 along its rear edge which engages notches in the upper movable card 78 so as to firmly secure the upper movable card in place. Extending downwardly from the portion 80 is a portion 85 which has a large cut-out portion to provide visibility and access to the ends of the contact springs. The portion 85 bends rearwardly and forms the portion 74 which is affixed to the armature 68.

As in the previously discussed embodiment, the cards and card-support structure has been specifically designed so that the cards may be removed and replaced by cards of different coding with a minimum of disturbance to the remainder of the relay and without the necessity of employing tools. Also, as in the previous embodiment, the coding of the relay is controlled by the shape of the aperture or slots in the lower movable card 77 and the upper fixed card 75.

As previously mentioned, a cover may be provided, in this embodiment, to enclose only the contact spring assembly. As shown in the accompanying drawings, the cover comprises a substantially U-shaped tube of non-magnetic material having an upper portion 86 and two side portions 87 the latter of which have small, inwardly extending flanges 88 to fit tightly under the projecting portions of the core as may best be seen in Fig. 10. The end of the cover may be enclosed with a piece of transparent material 89 to provide visibility of the relay's operation without the necessity of removing the cover.

The above description and the accompanying drawings are illustrative of the invention, but are not to be interpreted as limiting the scope of the invention to the particular embodiments presented.

What is claimed is:

1. In a relay, a core, an energizing coil on said core, an armature operatively associated with said core and attractable thereto upon the energization of said coil, a plurality of sets of contact springs, a fixed card of insulating material positioned adjacent the contact ends of said springs and contoured to normally hold certain of said springs in a deflected position, a card of insulating material carried by said armature and so contoured as to move certain other of said springs upon its movement, said cards each comprising two sections so constructed that each card may be replaced with a card of different contouring independently of the remainder of the relay.

2. In a relay, a support structure, a core removably supported by said support structure and comprising two detachably assembled portions, an energizing coil removably mounted on said core, an armature operatively associated with said core and attractable thereto upon the

energization of said coil, a plurality of sets of contact springs, a fixed card of insulating material positioned adjacent the contact ends of said springs and comprising two detachably assembled portions contoured to normally hold certain of said springs in a deflected position, a card of insulating material carried by said armature and positioned adjacent said card and comprising two detachably assembled portions so contoured as to move certain other of said springs upon its movement, said cards each being readily removable so that through the selection of the properly contoured card any desired contact code of make and break contacts may be secured in said relay.

3. In a relay, a core, an energizing coil on said core, an armature operatively associated with said core and attractable thereto upon the energization of said coil, a plurality of sets of contact springs, a fixed card of insulating material positioned adjacent the contact ends of said springs and comprising two detachably assembled portions contoured to normally hold certain of said springs in a deflected position, a card of insulating material carried by said armature and positioned adjacent said card and comprising two detachably assembled portions contoured so as to move certain other of said springs upon its movement, said cards each being readily removable so that through the selection of the properly contoured card any desired contact code of make and break contacts may be secured in said relay.

4. In a relay, a core, an energizing coil on said core, an armature operatively associated with said core and attractable thereto upon the energization of said coil, a plurality of sets of contact springs, a fixed card of insulating material positioned adjacent the contact ends of said springs and comprising a first portion having slots therein to accept said springs and a second portion having projections thereon engageable with certain of said springs so as to normally hold the certain of said springs in a deflected position, a card of insulating material carried by said armature comprising a first portion having slots therein to accept said contact springs and a second portion connectable to said first portion, and means individual to each of said cards for holding the two portions of each of said cards in a detachably assembled relationship whereby through the selection of the properly contoured cards any desired contact code of make and break contact sets may be secured in said relay.

5. In a relay, a support structure, a core removably supported by said support structure, an energizing coil removably mounted on said core, an armature operatively associated with said coil, a plurality of sets of contact springs arranged in two rows, a fixed card of insulating material positioned adjacent the contact ends of said springs and comprising a first portion having slots therein to accept said contact springs and a second portion having projections thereon engageable with certain of said contact springs to maintain said certain contact springs in a deflected position, a movable card positioned adjacent to said fixed card and comprising a first portion having slots therein to accept said contact springs and a second portion connectable to said movable card first portion and to said armature, said movable card being contoured so as to move certain other of said contact springs when it is moved by said armature, and means for enabling said cards to be detachably assembled

11

whereby through the selection of the properly contoured cards any desired contact code of make and break contact sets may be secured in said relay.

6. In a relay, a support structure, a detachably assembled core in two sections removably supported by said support structure, an energizing coil removably mounted on one section of said core, an armature operatively associated with said core, a plurality of sets of contact springs arranged in two rows, a fixed card of insulating material positioned adjacent the contact ends of said springs and comprising a first portion having slots therein to accept said contact springs and a second portion having projections thereon engageable with certain of said contact springs to maintain said certain contact springs in a deflected position, means to attach said fixed card to said support structure, a movable card positioned adjacent said fixed card and comprising a first portion having slots therein to accept said contact springs and a second portion connectable to said movable card first portion, and means to connect said movable card to said armature, said movable card being contoured so as to move certain other of said contact springs when it is moved by said armature, and means for enabling said cards to be detachably assembled whereby through the selection of the properly contoured card any desired contact code of make and break contact sets may be secured in said relay.

7. In a relay, a support structure, a spring pile-up assembly comprising a first row of contact springs, a first insulating block supporting said first row of contact springs, a second row of contact springs, a second insulating block supporting said second row of contact springs and mounted in juxtaposition to said first insulating block, a readily detachable clamp retaining said blocks in fixed interrelationship, a core removably supported by said support structure and by said spring pile-up assembly, an energizing coil removably mounted on said core, an armature operatively associated with said core, an armature-support spring affixed to said armature and removably mounted in said spring pile-up assembly, a fixed card of insulating material contoured to normally hold certain of said springs in a deflected position, and a movable card of insulating material removably mounted on said armature, the associated parts of the relay being so interattachable that the relay can be assembled without recourse to tools.

8. In a relay, a support structure, a spring pile-up assembly comprising a first row of contact springs, a first insulating block supporting said first row of contact springs, a second row of contact springs, a second insulating block supporting said second row of contact springs and mounted in juxtaposition to said first insulating block, a readily detachable clamp retaining said blocks in fixed interrelationship, a core removably supported by said support structure and by said spring pile-up assembly, an energizing coil removably mounted on said core, an armature operatively associated with said core, an armature-support spring affixed to said armature and removably mounted in said spring pile-up assembly, a fixed card of insulating material positioned adjacent the contact ends of said springs and comprising a first portion having slots therein to accept said contact springs and a second portion removably engageable with said first portion and having projections thereon engageable with certain of said contact springs to

75

12

maintain the certain of said contact springs in a deflected position, and a movable card connected to said armature comprising a first portion having slots therein to accept said contact springs and a second portion connected to said movable card first portion, said movable card being contoured so as to move certain other of said contact springs when it is moved by said armature.

10. In a relay, a support structure, a spring pile-up assembly comprising a first row of contact springs, a first insulating block supporting said first row of contact springs, a second row of contact springs, a second insulating block supporting said second row of contact springs and mounted in juxtaposition to said first insulating block, and a readily detachable clamp retaining said blocks in fixed interrelationship, a core removably supported by said support structure, an energizing coil removably mounted on said core, an armature operatively associated with said core, an armature-support spring affixed to said armature and removably mounted in said spring pile-up assembly, a fixed card of insulating material removably supported in fixed relationship to said core and contoured to normally hold certain of said springs in a deflected position, and a movable card of insulating material removably mounted on said armature and arranged to actuate certain other of said springs, the associated parts of the relay being so interattachable that the relay can be assembled without recourse to tools.

15. In a relay, a support structure, a spring pile-up assembly comprising a first row of contact springs, a first insulating block supporting said first row of contact springs, a second row of contact springs, a second insulating block supporting said second row of contact springs and mounted in juxtaposition to said first insulating block, a readily detachable clamp retaining said blocks in fixed interrelationship, a core comprising a first pole-piece removably supported at the front by said support structure and at the rear by said spring pile-up assembly, a second pole-piece removably supported by said first pole-piece and by said support structure, an energizing coil mounted on said second pole-piece, a rectangular armature operatively associated with said pole-pieces, an armature-support spring affixed to said armature and removably mounted in said spring pile-up assembly, a fixed card of insulating material removably supported by said support structure and contoured to normally hold certain of said springs in a deflected position, and a movable card of insulating material removably mounted on said armature and arranged to actuate certain other of said contact springs, the associated parts of the relay being so interattachable that the relay can be assembled without recourse to tools.

20. In a relay, a support structure, a spring pile-up assembly comprising a first row of contact springs, a first insulating block supporting said first row of contact springs, a second row of contact springs, a second insulating block supporting said second row of contact springs arranged to mate with said first row of contact springs, a third insulating block supporting coil leads and a contact protection network, and a readily detachable clamp retaining said blocks in fixed juxtaposition, a core removably supported by said support structure and by said spring pile-up assembly, an energizing coil removably mounted on said core, an armature

operatively associated with said core, an armature-support spring affixed to said armature and removably mounted in said spring pile-up assembly, a fixed card of insulating material removably supported in fixed relationship to said core and contoured to normally hold certain of said springs in a deflected position, and a movable card of insulating material removably mounted on said armature and arranged to actuate certain other of said contact springs, the associated parts of the relay being so interattachable that the relay can be assembled without the use of tools.

HENRY C. HARRISON.
